(57) **CLAIM**

The ornamental design for the display screen with graphical user interface, as shown and described.

DESCRIPTION

The sole FIGURE is a front view of a display screen with graphical user interface showing my new design.

The broken lines of uneven length show the display screen and form no part of the claimed design. The even length broken lines showing text and portions of the graphical user interface form no part of the claimed design.

1 Claim, 1 Drawing Sheet(56)
